VALVE

Joe Dunlap Seifer, Houston, Tex., assignor to
 Sinclair Refining Company, New York, N. Y., a
 corporation of Maine

Application May 1, 1931, Serial No. 534,308

6 Claims. (Cl. 251—93)

This invention relates to an improved two-way valve of special value in the handling of hot vapor mixtures from vapor phase cracking operations. These vapor mixtures are peculiarly difficult to handle prior to the separation of the tarry constituents which they normally contain as discharged, at temperatures upwards of 950° F., from the vapor phase cracking operation proper. Characteristically, these tarry constituents of such vapor mixtures tend to form deposits choking or plugging any stagnant spaces in lines or valves. The usual T connection to two gate valves to connect one line to either of two other lines for example, even where the legs of the T are very short and are connected directly to the gate valves, is not satisfactory for this purpose because, with the vapor mixture passing through either of the alternate passages a deposit tends to form in the stagnant leg of the T rendering the operation of the valve system uncertain and irregular. Two-way valves embodying plug-type closure members assist in the elimination of stagnant regions but in such service such valves tend to "freeze" in one position or to become locked in one position due to the development of "bridges" of hard coke between the closure member and the valve body. The improved valve of this invention is of special value in the handling of hot vapor mixtures from vapor phase cracking operations, as just noted, but it is of more general value where similar difficulties are encountered.

In the improved two-way valve of this invention, a relatively thin film of molten metal is maintained between a large part of the adjacent areas of the valve plug and the valve body which would otherwise contact. The lubricating effect thus secured in conjunction with the reduction of the area of direct contact between the valve plug and the valve body materially assist in maintaining the valve plug sufficiently free from its seat in the valve body to permit ready reversal of the valve when desired. This is accomplished by the provision of shallow recesses in those portions of the valve body forming the seat for the valve plug and by supplying a fusible metal or alloy of low melting point to these recesses as may be necessary to maintain them substantially full of the molten metal.

The invention will be further described in connection with the accompanying drawing which illustrates, in some detail, in Fig. 1 a section normal to the axis of the closure member of the valve and in Fig. 2 a section on line 2—2 of Fig. 1.

Referring to the drawing, the valve illustrated comprises a body 3 having three passages, 4, 5 and 6, and a plug-type closure member 7 arranged therein having two communicating ports, 8 and 9, adapted to register with passage 4 and either passage 5 or passage 6. The closure member 7 is shown positioned to permit flow between passages 4 and 6.

Shallow recesses 10, 11 and 12 are provided in the portions of the body 3 forming a seat for the closure member, or plug, 7 covering the greater part of the area of the body 3 with which the plug 7 would otherwise contact, these shallow recesses being connected at opposite ends by annular recesses 13 and 14. A ram 15 is provided for forcing a fusible metal or alloy, such as Wood's metal which has a melting point of 149.9—158° F. or Rose's metal which has a melting point of 194—210° F., into the space in these connected recesses between the plug 7 and the body 3 to maintain therein a film of metal molten at the temperatures prevailing in the valve during operation. The fusible metal or alloy used should advantageously have a melting point low enough to be maintained in a molten state in a ram positioned as is the ram 15 in the valve illustrated by the heat transmitted and radiated from the valve during operation.

In the drawing the present invention is illustrated as embodying a valve of the general type described and illustrated in an application filed February 26, 1929, Serial Number 342,904, by Eugene C. Herthel and Willis S. Gullette, now United States Patent No. 1,857,279. The two supplementary closure members 16 and 17 may be arranged for lubrication by molten metal in the same general manner, as illustrated in the drawing.

In operation, a small amount of molten metal or alloy is lost each time the valve is reversed, but this loss is minimized by closing the connection between the recesses containing the molten metal and the ram supplying the molten metal during the reversal of the valve. However, this loss is inconsequential compared to the advantages afforded by this type of lubrication of valves used for handling hot vapor mixtures from vapor phase cracking operations and the like.

The improved valve of the invention is of special value in apparatus for carrying out, for example, the processes described in an application Serial Number 341,214, filed February 19, 1929, by Harry L. Pelzer, now United States Patent No. 1,873,024.

I claim:

1. A valve comprising a body having three passages and a plug-type closure member arranged therein having two communicating ports 5 adapted to register with one of said passages and either of the other two of said passages, said body having shallow recesses over a substantial portion of the area of said body which otherwise would contact with said closure member, a molten metal or alloy filling said recesses and means 10 for supplying said molten metal or alloy to said recesses.

2. A valve comprising a body having three passages and a plug-type closure member arranged 15 therein having two communicating ports adapted to register with one of said passages and either of the other two of said passages, said body having shallow recesses over a major portion of the area of said body which otherwise would contact 20 with said closure member, a molten metal or alloy filling said recesses, and means for supplying said molten metal or alloy to said recesses.

3. A valve comprising a body having three passages and a plug-type closure member arranged 25 therein having two communicating ports adapted to register with one of said passages and either of the other two of said passages, said body having shallow recesses over a major portion of the area of said body which otherwise would contact 30 with said closure member, a molten metal or alloy filling said recesses, and means, including a reservoir, for supplying said molten metal or alloy to said recesses.

4. A valve comprising a body having three pas-

sages and a plug-type closure member arranged therein having two communicating ports adapted to register with one of said passages and either of the other two of said passages, said body having shallow recesses over a substantial portion 5 of the area of said body which otherwise would contact with said closure member, a metal or alloy fusible at a temperature below about 210° F. filling said recesses and means for supplying said metal or alloy to said recesses. 10

5. A valve comprising a body having passages and a plug-type closure member arranged therein having communicating ports adapted to register with said passages, said body having shallow recesses over a major portion of the area of 15 said body which otherwise would contact with said closure member, a molten metal or alloy filling said recesses, said molten metal or alloy acting as a lubricant, and means for supplying said molten metal or alloy to said recesses. 20

6. A valve suitable for handling hot vapor mixtures from vapor phase cracking operations comprising a body having passages and a plug-type closure member arranged therein having communicating ports adapted to register with said 25 passages, said body having shallow recesses over a major portion of the area of said body which otherwise would contact with said closure member, a metal or alloy solid at ordinary temperatures but molten at the temperatures to which 30 the valve is subjected filling said recesses, said metal or alloy acting as a lubricant, and means for supplying said metal or alloy to said recesses.

JOE DUNLAP SEIFER.
